UNITED STATES PATENT OFFICE.

JOHN R. SUNDEE, OF BUFFALO, NEW YORK, ASSIGNOR TO EDWARD WARNER, OF BUFFALO, NEW YORK.

SPRING-LID BOX.

No. 895,124.

Specification of Letters Patent.

Patented Aug. 4, 1908.

Application filed October 29, 1906. Serial No. 340,964.

To all whom it may concern:

Be it known that I, JOHN R. SUNDEE, a citizen of the United States, residing at Buffalo, in the county of Erie and State of New York, 5 have invented a new and useful Improvement in Spring-Lid Boxes, of which the following is a specification.

This invention relates to boxes or cases of that class having a catch for holding the cover 10 closed and a spring for automatically throwing the cover to its open position when released.

One of the objects of my invention is to simplify the construction and reduce the cost 15 of the catch and the spring.

A further object is to so combine the catch and the spring that the releasing movement of the catch increases the stiffness of the spring while the closing of the cover stiffens 20 the spring catch, causing it to more securely lock the cover.

In the accompanying drawings: Figure 1 is a perspective view of a jewelry box embodying the invention with the cover open, the 25 pad or cushion being omitted. Fig. 2 is a cross section thereof with the cover in the same position and the pad in place, and showing the position of the spring catch when pressed and about to return to its locking position. Fig. 3 is a similar section with the cover closed. Fig. 4 is a cross section of a 30 modified construction of the box with the cover closed and the pad omitted.

Similar letters of reference indicate corresponding parts throughout the several views.

A indicates the body and B the hinged lid or cover of the box which are both preferably stamped out of sheet metal, although they may be constructed of any other suitable material and made in any other desired form than that shown in the drawings.

The cover is provided on the inner side of its front wall with a suitable locking shoulder or projection c adapted to interlock with a 45 spring-catch d carried by the body of the box, so as to retain the cover in its closed position.

The catch shown in the drawings has an ordinary locking nose d¹ and is pressed inward for releasing it by a knob or button d², the 50 shank of which passes through the front wall of the box-body.

The catch is preferably formed integral with a bar E of resilient material, as spring brass which rests upon the bottom of the box- 55 body and extends from front to rear thereof,

the bar being held in place by lips f stamped up from the bottom and overlapping the bar.

g is a spring carried by the body of the box and adapted to be strained or deflected by the cover when the same is closed, so as to automatically open the cover when released. 60 In the preferred construction shown in the drawings, this spring is flat and formed in one piece with the bar E and said catch. It extends upwardly from the rear end of the bar to a point above the hinge of the cover and is bent rearwardly at its upper end and arranged to bear against the rear wall of the cover when the latter is closed. By this construction, upon closing the cover, the spring 65 is deflected forwardly, as shown in Fig. 3, and upon pressing the button d² to unlock the cover, the spring reacts and throws the latter open.

If desired, the spring g may also be utilized 75 as a stop to limit the opening movement of the cover. For this purpose, the spring is provided at its upper end with a hook g¹ which engages behind a lip or tongue h on the rear wall of the cover, as shown in Figs. 1 80 and 2.

The bar E which carries the catch d and the spring g is preferably capable of sliding lengthwise to a limited extent in the guides formed by the lips f, the bar being of the 85 proper length to permit of such longitudinal play between the front and rear walls of the body. By this construction, when the spring catch d is pressed inward to release the cover the bar E is shifted rearwardly, increasing 90 the stiffness or resilience of the spring and improving its action, while when the cover is closed the resultant pressure against the spring causes the bar E to be shifted forwardly, increasing the stiffness of the spring 95 catch d in like manner and causing it to more reliably interlock with the cover. This reciprocal stiffening action of the spring-catch and the cover-opening spring is obtained by the simple expedient of connecting the catch 100 and the spring by a bar or carrier which is free to slide back and forth to the necessary extent. At the same time, the integral construction of the catch and the spring materially reduces the cost of these parts and 105 facilitates their attachment to the box.

As the connecting bar E lies flat on the bottom of the box and its fastening lips f project but slightly above the bottom, they do not interfere with the pad or cushion I of the 110

box. The spring also does not interfere to an objectionable extent with the usual neck J of the box, and as it is stiffened in the act of releasing the cover, it may be formed with 5 less curve or bulge than could be the case if this feature were absent, thus correspondingly reducing the extent to which the spring indents the neck. The lips f while permitting the bar E to slide lengthwise, as above 10 described, prevent it from rocking on the bottom of the box, thus effectually holding the spring catch as well as the spring from displacement.

If desired, the stop-tongue h and stop-hook g¹ may be omitted, as shown in Fig. 4.

It is obvious that the spring g can be made longer or shorter to cause it to open the cover to a greater or less extent or at different angles to the body of the box.

20 The improvement is herein shown in connection with a jewelry box, but it may obviously be applied to other boxes of various kinds.

I claim as my invention:

25 1. In a box, the combination of a body, a hinged cover, a bar arranged within the body and resting upon the bottom thereof; said bar being provided at its front end with a spring-catch adapted to interlock with the 30 cover and at its rear end with an opening-spring arranged to act against the cover, and means for attaching said bar to the bottom of the box-body, substantially as set forth.

2. In a box, the combination of the body,

a hinged cover, and a bar extending along the 35 bottom of the body and having its front end bent upward to form a spring catch adapted to interlock with the cover and having its rear end bent upward to form a cover-opening spring, the bottom of the body having retaining lips which overlap said bar, substantially as set forth.

3. In a box, the combination of the body, a hinged cover provided on the inner side of its rear wall with a stop, a bar secured to the 45 bottom of the body and having its front end bent upward to form a spring-catch adapted to interlock with the front portion of the cover and having its rear end bent upward to form a cover-opening spring, said spring terminating in a hook arranged to engage the cover-stop, substantially as set forth.

4. In a box, the combination of the body provided in its bottom with guides, a hinged cover, and a sliding bar resting on the bottom of the body and arranged in said guides, said bar being provided at its front end with a spring-catch adapted to interlock with the cover and at its rear end with a cover-opening spring which bears against the cover, 55 substantially as set forth.

Witness my hand this 25th day of October, 1906.

JOHN R. SUNDEE.
